UNITED STATES PATENT OFFICE.

EUGENE N. GATES, OF HOLLISTON, MASSACHUSETTS, ASSIGNOR OF TWO-THIRDS TO W. E. PUTNEY, OF FITCHBURG, MASSACHUSETTS, AND CHARLES H. CHAPMAN.

DESIGN FOR A BICYCLE-FRAME.

SPECIFICATION forming part of Design No. 26,263, dated November 10, 1896.

Application filed July 17, 1896. Serial No. 599,566. Term of patent 14 years.

To all whom it may concern:

Be it known that I, EUGENE N. GATES, of Holliston, in the county of Middlesex and State of Massachusetts, have invented and produced a new and original Design for Bicycle-Frames, of which the following is a specification, reference being had to the accompanying drawings, forming a part hereof.

Figures 1 and 2 represent side views of bicycle-frames embodying my design; and Fig. 3 represents a perspective view of the rear portion of a frame, showing the leading features of the design.

The leading features of my design consist in a main frame comprising a portion which presents a circular arc when viewed from the side and a portion which presents a circular arc within the first-mentioned portion and curved in the opposite direction thereto.

a represents the main portion of a bicycle-frame, the portion 2 of which presents a circular arc from one side. Another portion, 3, presents a circular arc extending across the space within the portion 2 and curved in the opposite direction thereto. 25

I claim—

The design for a bicycle-frame, substantially as shown and described.

In testimony whereof I have signed my name to this specification, in the presence of two subscribing witnesses, this 23d day of June, A. D. 1896. 30

EUGENE N. GATES.

Witnesses:

A. D. HARRISON,
P. W. PEZZETTI.
